SHELF SUPPORT

Charles W. Attwood, Wayne, Mich.

Application November 20, 1950, Serial No. 196,687

3 Claims. (Cl. 248—243)

1

The present invention relates to shelf supports and specifically to shelf supports adapted for use with upright channel section members such as those shown in U. S. Letters Patent No. 2,345,650, issued April 4, 1944, to the present inventor.

In that patent there is shown a channel member consisting of a strip of sheet metal bent laterally to form a rectangular channel having its edges bent toward each other at right angles and then downwardly toward the bottom wall of the channel, also at right angles, leaving an open lengthwise slot between short inturned flanges.

The present invention has among its objects the provision of a shelf supporting element easily and quickly attached to such a channel member arranged in an upright position.

Another object is the provision of such an element attached without the use of bolts or screws and in any location lengthwise of the upright member.

Still another object is such a shelf support that is provided with means for preventing displacement of a shelf being supported thereby.

Other objects and advantages will be apparent to those skilled in the art upon reference to the following description and the accompanying drawings in which

Fig. 1 is a more or less diagrammatic view of a set of shelves indicating the use of the support.

Fig. 2 is a perspective phantom view showing one of the supports in position on an upright.

Fig. 3 is a top plan view of the same.

Fig. 4 is a side elevation of the same, showing a portion of a wood shelf.

Fig. 5 is a view as from the right of Fig. 4, but showing two adjacent shelves.

In Fig. 1 there is indicated, more or less diagrammatically, a shelf unit consisting of a plurality of upright members 10, it being understood that other uprights, not visible, are used to provide in plan a rectangular or other shaped structure. These may be suitably fixed together with cross members and diagonal braces if desired. These members 10 will be channel members of the form indicated at 10 in Figs. 2 to 5 and as shown in the prior patent above referred to. The uprights 10 will be so arranged as to present the open slot inwardly of the structure.

The shelf support, shown as a whole at 15, consists of a U-shaped piece of spring metal, the legs of which are each provided with a hook portion 15A bent outwardly from the plane of the leg metal and located adjacent the leg end. Each leg is also provided with wing abutment 15B bent

outward at right angles to the plane of the leg metal and having its lower or active edge 15C normal to the outer line of the support member.

The hook 15A and abutment edge 15C are spaced lengthwise of the U-shaped support a distance that is substantially the depth of the flange 10A turned inwardly along the open slot in the member 10. The hook 15A is also at the upper edge of the leg metal, while the edge 15C of the abutment 15B is at the lower edge thereof.

As indicated in Figs. 2 to 5, the member 15 is inserted in a member 10 by squeezing together the hook ends and after insertion in the slot, allowing the legs to spring apart under the flanges 10A. In order to do this, the member 15 must be tilted upwardly, so that the nose of the hook will pass under the flange 10A.

When this has been done, the member is brought down to the position shown so that the abutment 15B rests against the portion 10B of member 10, this being the face between the open slot and the side wall.

To retain the member 15 in this position against accidental dislodgement, suitable bumps or low projections 16 may be formed in the leg metal and located so that they will underlie the inner edge of a flange 10A when the member 15 is in position. Further, the upper edge of the support member 15 will be provided with sharp projections 17 adapted to penetrate a wooden shelf such as is indicated at 18.

In Fig. 5 there are shown two wooden shelves 18 having their adjacent edges maintained in position by the projections 17. The same support 15 may also be used to support metal shelves or boxes, but in this case, suitable openings in the shelves or boxes must be provided for the reception of the projections 17.

I claim:

1. Shelving comprising upright frame elements each consisting of rectangular channeled members having open slots of less width than the members and provided with flanges extending inwardly of the channels along said slots, and shelf supports consisting of U-shaped elements of resilient material adapted to project into said slots and provided on their upper edges with hooks adapted to embrace said flanges and on their lower edges with abutments adapted to rest against the faces of said channeled members between the slot and the outer walls.

2. Shelving as set out in claim 1 in which the shelf supports are provided with means to prevent accidental dislodgement.

3. In combination with a rectangular frame

2

member having a longitudinal slot in one of its faces and having flanges at the edges of said slot extending inwardly and at right angles to the adjacent outer surface of the member, a support for a shelf or the like consisting of U-shaped element of resilient material having at the upper edges of its legs, hooks embracing and engaging the inner edges of said flanges and having at the lower edges of said legs abutments engaging the outer face of the frame member, said U-shaped element being engageable with or disengageable from said frame member by squeezing together the legs and passing said hooks through said slot.
